DESIGN FOR A TRACTOR

Alexis de Sakhnoffsky, Philadelphia, Pa., assignor to The White Motor Co., Cleveland, Ohio

Application July 20, 1937, Serial No. 70,542

Term of patent 7 years

To all whom it may concern:

Be it known that I, Alexis de Sakhnoffsky, a subject of the Czarist Regime of Russia, residing at Warwick Hotel, city of Philadelphia, in the county of Philadelphia and State of Pennsylvania, have invented a new, original, and ornamental Design for a Tractor, of which the following is a specification, reference being had to the accompanying drawing, forming part thereof.

Fig. 1 is a side elevation of a tractor of my design.

I claim:

The ornamental design for a tractor as shown.

ALEXIS DE SAKHNOFFSKY.
